UNITED STATES PATENT OFFICE.

JOHN PEARSON, OF CHICAGO, ILLINOIS.

CAR-ROOF.

1,105,828.

Specification of Letters Patent.

Patented Aug. 4, 1914.

Application filed August 18, 1911. Serial No. 644,756.

To all whom it may concern:

Be it known that I, JOHN PEARSON, a citizen of the United States, residing at Chicago, in the county of Cook and State of Illinois, have invented certain new and useful Improvements in Car-Roofs, of which the following is a specification, reference being had therein to the accompanying drawing.

0 My invention relates to metallic car-roofs, and consists in the novel and useful combinations and organizations of parts herein described and then pointed out in the appended claims.

5 One of the objects of the present invention is to provide a new and improved arrangement of parts whereby the distance between the roof-panels and overhanging carline-flanges will be uniform and predetermined by the depth of the carline-web in order 20 that the inturned ends of the carline-caps may be made uniform and provide a storm-tight joint.

Other objects are to provide a sectional 25 ridge-cover whose parts shall lie between and flush with the adjacent carline-caps; to provide a ridge-cap covering and interlocking with the adjacent ends of an opposite pair of carline-caps and an opposite 30 pair of ridge-cover sections; and to provide that the bolts holding the ridge-caps shall connect metallic parts so as to avoid the looseness that would be consequent on the interconnection of wooden and metal parts.

35 Other objects will be apparent from the disclosure which is made in connection with the accompanying drawings showing practical embodiments of the various parts of my invention, and in which—

40 Figure 1 is a top plan view of part of a car roof embodying the several features of my present invention with various parts cut away to afford better illustration; Fig. 2 is a cross-sectional view of one side of the 45 car-roof taken on line 2—2 of Fig. 1; Fig. 3 is a detail sectional view showing the parts at the crossing of a purlin and carline taken on the line 3—3 of Fig. 2; Fig. 4 is a detail end-view taken at the end of 50 one of the carlines at the eaves with the downturned end of the carline-cap broken away; Fig. 5 is a cross-sectional view on the line 5—5 of Fig. 1 showing one of the carlines and its end-brace in position with 55 reference to a side-plate; Fig. 6 is a per-

spective plan view of one of the end-braces or brackets of the carlines; Fig. 7 is a cross-sectional view at the junction of the ridge-pole and one of the carlines taken on the line 7—7 of Fig. 4; Fig. 8 is a longitudinal cross-sectional view of the same parts taken on the line 8—8 of Fig. 7; Fig. 9 is a view of the same parts in horizontal section being taken on the line 9—9 of Fig. 8; Fig. 10 is a perspective view of 60 one of the carline-caps, and Fig. 11 is a similar view of one of the sections of the ridge-cover.

In the drawings the reference numeral 12 designates the ridge-pole, 13 the side 70 plates, 14 the carline-brackets or braces bolted to the side-plates at intervals along their length, and 15 the longitudinal wooden purlins.

Extending transversely of the car at suitable intervals are the metal carlines which in the present invention are double trough-shape in cross-section extending from side to side of the car and resting upon the side-plates and ridge-pole into which they are 80 stepped as shown in Fig. 2. Each carline comprises a lower horizontal flange 16, lower vertical webs 17, intermediate horizontal flanges 18, upper vertical webs 19, and upper lateral flanges 20, the horizontal flanges 16 being extended beyond the side-webs and side-plates of the car and bent down to form seats for the side-plates as at 21. The carlines are stepped into the side-plates, purlins 85 and ridge-pole a distance slightly less than the depth of the vertical webs 17 so that the intermediate horizontal flanges 18 rest on these parts, and the webs 17 and flanges 18 form angular seats in the carlines in which these parts rest, the purlins, ridge-pole and side-plates being cut-out or recessed somewhat in excess of the length of the webs 17 90 in order to provide a clearance between them and the flanges 16 and that the carline-seats shall rest thereon. The carlines are connected to the ridge-pole, purlins and side-plates by bolts or other suitable connecting devices as clearly shown at 22 in 100 Figs. 1 and 2, so that the carlines carry the purlins and the superposed roof-sheets. The flanges 20 of the carlines are substantially straight from end to end so that the width of the carlines is approximately uniform throughout their length, and the webs 17 and 19 are of uniform height, respec-

105 110

tively. The roof sheets or panels 23 extend from the ridge pole outward to the eaves resting upon the purlins, and each sheet or panel is substantially rectangular in shape and is provided with upturned side-flanges 24, an upturned inner or ridge-flange 25, and a downturned outer flange or end 26 adapted to extend down upon and be fastened to the outer face of the side-plates. 5 The side-flanges 24 of the panels lie under the flanges 20 of the carlines, with sufficient clearance between the parts 19, 20 and 24 to allow play to the latter along their length. 10 The carline-caps are of metal and are of inverted trough-shape in cross-section consisting of an upper horizontal portion 27 of sufficient width to overlap the carline-flanges 20 and adjacent flanges 24 of a pair of roof-panels or plates, downturned sides 28, and inwardly and upwardly extending side-flanges 29; and they extend from the ridge-pole where each is provided with an upturned cross-flange 30 outwardly to the eaves where each is provided with a downturned outer end 31 overlying the downturned portions 21 and 26 of the carlines and roof-panels, the bolts 22 passing through the downturned portions 21 and 31 and the side-plates. 15 After the roof-plates are assembled upon their supporting purlins on each side of the carlines, the carline-caps are slipped into place, each along the length of the associated carline from the eaves to the ridge-pole and covering the flanges 24 of the adjacent panels beginning at the outer end, and when each cap is in position its downturned sides cover the lateral flanges 20 of its carline and overlap the upturned flanges 24 of the associated panels, 20 leaving a clearance so that the latter flanges are free to move or play under strains or twisting actions of the car. The webs 17 and 19 are of uniform height respectively along the length of the carlines, and as the recesses in the purlins, side-plates and ridge-pole are of greater depth than the webs 17 and as the carline-seats formed by the flanges 18 rest on these parts the distance 25 between these parts and the flanges 20 is uniform so that the flanges 29 of the carline-caps, being made of such height as to fill the space between and press against the panels and the underside of the flanges 20, hold the panels in place and provide a watertight joint. 30 By this organization the roof-plates are interlocked with the carlines in such manner as to retain them in position but permit them to have play or movement under any strains to which the car may be subjected, the side flanges of the panels have room for play between the carlines and the downturned sides of the caps. The carlines being stepped into the purlins brace each purlin from the adjacent ones instead of merely from the end-frame of the car, and

the purlins also brace each carline from the adjacent ones; and the carlines being also stepped into the ridge-pole and side-plates brace these parts. The carlines are connected to the side-plates also by means of the metallic end-braces or brackets 13 which are V-shape in general contour the apex being bolted or riveted to the flange 16 of the carline and the ends being similarly secured to the side-plate on each side of the carline. 7 The arms of the brace are provided with upturned flanges 14 intermediate the side-plate and webs 17 of the carlines to straddle the carlines, being beveled to lie flush, there-with, and to brace the carlines and side-plates. 80

I also provide a sectional metallic ridge-cover, each section being located between a pair of adjacent carline-caps at the ridge or center and extending longitudinally of 85 the car and over the upturned inner or ridge-flanges 25 of an opposite pair of roof-plates upon which its opposite flanges or wings rest. Each section of the ridge-cover consists of a trough-shaped structure comprising a top or upper portion 32 and downturned sides 33 having lateral flanges 34 adapted to overlie and rest upon the upper faces of a pair of opposite plates or panels 23 with the upper flanges 25 thereof in the 90 trough provided by the sides and top. The top and sides are provided respectively with upwardly and laterally bent wings or flanges 35 and 36, the latter lying flush against the sides 28 of adjacent associated 100 panel-caps to protect the opening or space between these parts, and the former lying under and interlocking with a malleable cap-plate which is bolted to an associated carline and holds an opposite pair of carline-caps and the adjacent opposite sections of the ridge-cover in place and also provides a base for a running-board saddle or support. Each cap is provided with a raised central portion 37 and four lateral 105 arms 38 and 39 arranged in opposite pairs and trough-shape in cross-section. The arms 38 are oppositely inclined to fit the pitch of the roof, and are below the plane of the top 37 to provide shoulders 40. The 110 arms 39 are offset as at 41 so as to be below the plane of the top of the arms 38 and to provide a shoulder 42. Each arm 38 fits over the inner end of a carline-cap, the flanges 30 of which rests under the top 37 115 and adjacent the shoulders 40, and each arm 39 fits over the end of one of the sections of the ridge-cover, the flange 35 of which rests behind a shoulder 42. In assembling the parts the carline-caps and the ridge-cover sections are placed in position with their respective flanges 30 and 35 arranged in adjacent position at the crossing of each carline with the ridge-pole, and the ridge-caps are then placed over 120 125 130

these flanges and bolted in place by the bolts 43 which pass through the lower horizontal flanges 16 of the carlines. By this arrangement the malleable ridge-caps are secured to the metal carlines instead of to the wooden ridge-pole as heretofore, so that looseness due to differences in shrinkage and wear of the wood and metal is obviated, and the adjacent sections of the ridge-cover and the inner ends of opposite carline-caps are held in place by a single connecting cap. The saddles 44 of the running-boards 45 are stepped over the ridge-caps so as to be held against displacement sidewise of the car and the through bolts 43 pass up through the saddles which are cut-away to receive the intermediate nuts which clamp the caps in place, the grip-nuts 47 holding the saddles on the caps.

I claim:

1. In a car roof, a series of carlines extending transversely of the car and each having top flanges, a series of metal panels extending from the side to the center of the car between the carlines and having upturned side-flanges under the flanges of the carlines, and caps extending from the side to the center of the car and covering the carlines and upturned flanges of adjacent panels and having their sides inwardly and upwardly bent to engage the body of the panels and underside of the carline-flanges.

2. In a car roof, a series of carlines having vertical webs and upper flanges, a series of metal panels with side flanges extending under the flanges of the carlines and spaced from the carline-webs, and caps covering the flanges of the carlines and the flanges of adjacent panels and having inner side-flanges extending under and against the carline-flanges and resting on the panels at a distance from the panel-flanges.

3. In a car roof, a plurality of carlines having vertical webs and upper flanges, a plurality of metal panels having side flanges under the carline-flanges, and carline caps each having a top and sides covering the joint between two panels, the sides of the cap being inturned under the carline-flanges and resting on the panels outside the panel-flanges.

4. In a car roof, a series of mortised purlins, a series of carlines having parts in the mortises of the purlins and flanges seating on the purlins and having upper vertical webs and lateral flanges, metal panels having upturned sides under the flanges of the carlines, and caps having tops and sides covering the joints between the panels, the sides of the caps being inturned under the

carline-flanges and filling the space between said flanges and the panels.

5. In a car roof, a series of mortised purlins, a plurality of carlines having lower webs and flanges seating on the purlins and having upper webs and lateral flanges above the purlins, metal panels resting on the purlins between the carlines and having upturned flanges adjacent the upper carline-webs and under the carline-flanges, and carline-caps of inverted trough shape having tops and sides, the latter having flanges in-turned under the carline-flanges and resting against the panels outside their flanges and against the carline-flanges.

6. In a car roof, a series of panels, a series of caps extending from the ridge to the eaves and having upturned ridge-flanges, each cap covering the joint between a pair of panels, a ridge cover for the opposite panels composed of trough-shape sections, each section having lateral wings at its ends resting against adjacent caps and having upturned end flanges, and ridge-caps each interlocking with the ridge-flanges and upturned end flanges of an adjacent pair of panel-caps and ridge-sections.

7. In a car roof, a series of metal carlines having top flanges, a series of panels, a series of carline-caps extending from the ridge to the eaves, each cap covering the joint between a pair of panels, and a ridge cover composed of metallic sections, each section having a top with upturned ends and lateral wings abutting against an adjacent pair of carline-caps and downturned sides resting on opposite panels between said caps.

8. In a car roof, side-plates, a ridge-pole, a series of mortised purlins, a series of metallic body-carlines extending the width of the car and each having a lower flange and vertical webs in the mortise of a purlin and intermediate horizontal flanges seated on the purlins and upper vertical webs and flanges spaced above the purlins, metallic panels on the purlins intermediate the carlines and having upturned flanges lying under the carline-flanges, and caps on the carlines covering the upturned flanges of adjacent panels and having their sides inturned to form flanges filling the space between the panels and carline-flanges.

In testimony whereof I affix my signature in presence of two witnesses.

JOHN PEARSON.
